UNITED STATES PATENT OFFICE.

CARLISLE FORREST SMITH, OF JERSEY CITY, NEW JERSEY, ASSIGNOR TO BOURNONVILLE ROTARY VALVE MOTOR COMPANY, OF HOBOKEN, NEW JERSEY, A CORPORATION OF NEW JERSEY.

ROTARY VALVE.

Application filed February 15, 1923. Serial No. 619,176.

The invention relates to rotary valves, and particularly to internal combustion engines having rotary valves controlling the intake and exhaust of the gases. The object of 5 the invention is to provide certain improvements upon and within my Patent No. 1,442,705 of January 16, 1923, as herein-after more particularly pointed out and claimed.

10 In the accompanying drawings forming part hereof:

Fig. 1 is a vertical transverse section through the valve mechanism and the upper part of one of the cylinders of a multi-cylinder internal combustion engine;

15 Fig. 2 is a vertical longitudinal section on the line 2—2 of Fig. 1;

Fig. 3 is a fragmentary sectional elevation; and

20 Fig. 4 is a vertical longitudinal section showing a modification.

The numeral 1 designates a cylinder block, and 2 a separate head, the parting or joint being marked 3. The engine will be understood as comprising a plurality of cylinders, of which the one in the plane of the section is marked 4. The head and the adjoining portion of the cylinder block together form a casing for a rotary cylindrical valve member or plug 5, which extends longitudinally over the tops of the cylinders, preferably in two or more flexibly jointed sections as is familiar.

The valve casing contains an incomplete 35 cylindrical bore 6, at the bottom of which is a port communication 7 to the combustion chamber 8 of the cylinder, while at opposite sides are an intake manifold and port 12, 11 and an exhaust port and passage 10, 9. The cylindrical bore curvature forms seats 60 and 61 at opposite sides of the cylinder port, between the same and the intake and exhaust ports, respectively, and a seat 62 at the opposite side of the exhaust port 40 from the seat 61, that is to say between the exhaust port and the chamber 14 herein-after referred to. At the intake side the bore is preferably relieved or enlarged above the intake port and between the same and the chamber 14 as shown at 6^a. The valve member is formed with pocket ports 13 in its

sides which are properly positioned to connect the cylinder port 7 alternately with the intake and the exhaust at the proper times. The valve is suitably connected with 55 the crank-shaft to rotate always in one direction, the direction of rotation being indicated by the arrow.

The portion 14 of the valve chamber above the fixed bore and opposite the port 7 is 60 formed to accommodate a shoe 15, or mobile part of the casing, having a segmental under face substantially conforming to a considerable portion of the cylindrical surface of the valve member, it being understood, of course, 65 that the curvature of the shoe like that of any bearing is of somewhat greater radius than the rotating member. Above, that is to say, back of, the shoe, at the top of the chamber 14 is a straight transverse, inclined, 70 rigid way or slide surface 18, against which the shoe is supported through the intermediary of a slide or wedge 16 having a sloping back 17 affording an extended sliding surface, the slope or taper being transverse to 75 the shoe and valve and contrary to the direction of rotation of the valve member and being at a low angle to the line or tangent which is at right angles to the central line passing through the port 7, the center of the 80 valve member and through or near a rocker joint or point of tilting support, the present preferred form of which will now be described.

The shoe is provided centrally or in the 85 central line with an opening 40, into which is inserted, from above, the cylindrical stem 41 of a ball or hemispherical joint member 19. The slide or wedge member 16 is formed on its face with a socket corresponding to the ball, the two forming a universal joint between the two members of the movable structure of the compensating device, which permits the shoe to rock or tilt both 90 transversely and longitudinally, and in fact to pivot in any direction, always governed by and in conformity to the valve member. The point of support is substantially central with respect to the ends as well as the sides 95 of the shoe, and proper spaces are left in the chamber 14 to allow for the complete mobility of the shoe.

As in my prior patent, the slide or wedge member and the shoe are pressed in the direction of the taper and contrary to the direction of rotation of the valve member by a spring 20 located in a spring chamber 21 and pressing against the broad end of the wedge. The spring means opposes the circumferential movement of the shoe in one direction and presses the shoe against the valve member and the latter to its seat in the fixed bore, so as constantly to hold the valve tight irrespective of expansion and contraction or wear. The slope of the wedge and wedge-way is too low to permit the wedge to yield to the force of the explosions or of the compression or the exhaust, the wedge being self-holding in this respect. If, however, the valve tends to stick, owing to expansion, the increased frictional drag of the valve member on the shoe, transmitted through the articulation or toggle, forces the parts slightly against the springs and thereby automatically relieves the condition. Slight radial movement of the shoe, in or out with respect to the center of the valve, is thus obtained by virtue of true circumferential movement in one direction or the other. The springs are of such strength as to resist normal frictional drag sufficiently to secure the desired tightness.

By virtue of the capacity of the shoe for longitudinal tilting, added to its capacity for transverse tilting, it is insured that the shoe will conform and bear evenly upon the valve member throughout the length of the shoe, both initially and during all movements either of the valve member or of the shoe. In rotary valves for internal combustion engines the amount of permissible deviation from absolute accuracy in the bearing surfaces is extremely small, owing to the great heat and the exposure of the valve member to the combustion gases on the one hand and the necessity of maintaining a good seal on the other hand. It results that there is a range of a few thousandths of an inch within which there can be satisfactory operation, variations above one limit causing excessive loss of power and variations below the other limit resulting in destructive binding and cutting.

There are three sets of bearing surfaces,—one between the valve member and the bottom of the casing, another between the top of the valve member and the shoe, and the third between the slide or wedge and the slide surface of the casing. All of these are theoretically parallel in the longitudinal direction, but slight inaccuracies of manufacture are inevitable, and even with great care very minute inaccuracies in the several places are likely to mount up to a total which, though small actually, is sufficient to derange the operation of the valve. The present construction overcomes this dif-

ficulty, renders manufacture less exacting, and secures the further important advantage of rendering the shoes interchangeable.

Other forms of the double or universal rocker may be employed, but the construction illustrated possesses special advantage in ease of manufacture. Furthermore, as illustrated in Fig. 3, it permits of the compensating device being restored to full operativeness after the various parts have worn to such an extent that the wear can no longer be taken care of automatically. At such time all that is necessary to do is to remove the shoe or shoes, take the ball member 19 out of the shoe, and replace it with one or more washer-like shims 42 between its shoulder and the back of the shoe, thus varying the spacing between the shoe and its movable backing member 16.

As seen in Figs. 2 and 4, each shoe is of limited longitudinal extent. As disclosed in the patent to Eugene M. Bouronville No. 1,472,113, dated October 30, 1923, there are preferably two or a plurality of the shoes for each section of the valve member, so that the shoes can have slight independent or relative movement on different portions of the valve section. Fig. 2 illustrates a construction in which there is a separate spring-pressed wedge or slide for each shoe. Similar functioning can be secured with greater advantage in manufacturing by combining two or more shoes with a common wedge or slide 16^a jointed to the shoes by separate ball joints. In this case, if one shoe moves circumferentially of the valve member somewhat farther than the other owing to a difference in conditions at the two regions, the common wedge will skew slightly on its slideway.

Returning to the preferred construction of the bearing for the valve, it will be seen that the total fixed bearing is confined to an arc which includes the seats 60, 61 and 62 and the cylinder and exhaust ports 7 and 10, this arc being subtended by a chord passing diagonally to include these regions and being materially less than 180°. The valve member does not touch at the enlarged region 6^a of the casing extending between the intake 12 and the compensating device chamber 14, the entire additional bearing for the valve member being provided by the yielding shoe 15. I find that a valve member left free in this manner is yet kept perfectly seated, so as to avoid any leakage or straying of intake and exhaust gases that would interfere with the operation of the engine or impair its efficiency. However great the expansion of the valve member due to heating by the hot gases, it can not seize or become bound in the bearing, and consequently the clearance, that is to say the difference between the radii of the valve member and of the fixed bearing seats can be very

slight, which is in turn favorable for good seating.

Various other modifications and changes in form and detail may be made without departing from the invention.

What I claim as new is:

1. An internal combustion engine valve having a rotary valve member and a casing communicating with the combustion chamber, a compensating device comprising a shoe bearing on the curved surface of the valve member and movable circumferentially thereon in response to variations in the drag of the valve member which is opposed by a spring, and backing means for the shoe causing the shoe to recede from or approach the center of the valve member according as the shoe moves circumferentially in one direction or the other, the shoe being completely supported by the backing means at a region central with respect to its sides and ends so as to be free to tilt both transversely and longitudinally while performing its compensating functions.

2. In a rotary valve having a rotary valve member and a casing, an automatic compensating device comprising a two-part movable structure having its parts connected by a universal joint, one of the parts being a shoe which is movable circumferentially on the valve member while the other part executes a different movement to cause simultaneous slight recession or approach of the shoe.

3. In a rotary valve, a valve member, a casing having a guide, a slide movable on said guide transversely of the valve member, a circumferentially movable shoe bearing on the valve member, and a ball joint between said slide and shoe.

4. In an internal combustion engine, a rotary valve member, a valve casing having a port communicating with the combustion chamber and a transversely inclined guide opposite said port, a spring-pressed wedge or slide movable on said guide, a shoe bearing on the valve member, and a universal rocker joint between said wedge and shoe.

5. In a rotary valve having a rotary valve member and a casing, an automatic compensating device comprising a backing guide or

way and a two-part movable structure having its parts connected by a rocker joint, one of the parts being a shoe the face of which obediently follows the contour of the valve member while the other part slides on the 55 backing guide, and means in connection with the rocker joint for varying the spacing between the slide and the shoe.

6. In a rotary valve having a valve member, and a casing, an automatic compensating device comprising a transversely movable slide member and a circumferentially movable shoe member, one of said members having a central opening and the other a ball socket, and a ball engaging said socket 65 and having a stem inserted in said opening.

7. In a rotary valve having a valve member, and a casing, an automatic compensating device comprising a shoe movable circumferentially of the valve member, and a 70 spring-pressed backing member guided in the valve casing, and a ball engaging a socket in one of said members and having a stem set into the other member.

8. A rotary valve of the kind described, 75 comprising a casing having a port to communicate with a cylinder, intake and exhaust ports on either hand of such cylinder port, and a chamber at the far side opposite from the cylinder port, a rotary valve member 80 adapted to connect the cylinder port with the exhaust port and then with the intake port, and an automatic compensating device in said chamber having a shoe bearing upon the valve member, said casing being formed 85 with fixed arcuate bearing seats at opposite sides of the cylinder port, that is to say between the cylinder port and the intake and exhaust ports respectively, and also at the side of the exhaust port away from the cylinder port, that is to say between the exhaust port and the compensating device chamber, the interior of the casing between the intake port and the compensating device chamber 90 being enlarged, the total arc of fixed bearing 95 being subtended by a chord passing diagonally to include said seats and the cylinder and exhaust ports and being less than 180°.
